UNITED STATES PATENT OFFICE.

CHARLES H. NUMAN, OF NEW YORK, N. Y.

DESIGN FOR AN INKSTAND.

41,589.

Specification for Design.

Patented July 18, 1911.

Application filed April 19, 1910. Serial No. 556,452. Term of patent 7 years.

To all whom it may concern:

Be it known that I, CHARLES H. NUMAN, a citizen of the United States, residing at New York city, in the county and State of New York, have invented a new, original, and ornamental Design for an Inkstand, of which the following is a specification, reference being had to the accompanying drawings, forming a part thereof, and in which—

Figure 1 is a plan view, Fig. 2 a side ele-

vation, and Fig. 3 a front elevation of an inkstand embodying my design.

I claim:

The ornamental design for an inkstand, as shown.

CHARLES H. NUMAN.

Witnesses:

CHARLES W. MEYRICK,
W. S. HOSKINSON.
